UNITED STATES PATENT OFFICE.

EDWARD L. WAGNER, OF PORT WASHINGTON, NEW YORK.

SEWER-FLUSHING APPARATUS.

No. 866,244.

Specification of Letters Patent.

Patented Sept. 17, 1907.

Application filed April 11, 1907. Serial No. 367,523.

To all whom it may concern:

Be it known that I, EDWARD L. WAGNER, a citizen of the United States of America, and a resident of Port Washington, Nassau county, State of New York, have

5 invented certain new and useful Improvements in Sewer-Flushing Apparatus, of which the following is a specification.

My invention comprises an automatic siphon device for flushing sewers or for the rapid automatic discharge 10 of sewage or water from filter works of various kinds including septic tanks, contact beds, percolating filters, sand filters, &c.

The accompanying drawing represents a vertical section of a flush tank with the siphon set therein.

15 The flush tank H may be built of any material such as brick, concrete, or stone, &c., it being necessary only to secure a tight compartment. I is a constantly open fluid inlet thereto. The siphon as usually constructed is of cast iron, although other material may be used, 20 viz: terra cotta or cement. The siphon consists of an intake leg A, which is of varying length to suit the draft of the siphon used. The bend B is provided with two bells, one b, for the intake leg A, and the other b', for the discharging leg C. These two legs are leaded into 25 this bend B. The bend is of varying diameter commencing at 4" and ending at 3". These being the sizes indicated on this drawing, although the capacity of discharge may be increased or decreased by increasing or decreasing the bore of the pipe and bend. The vent 30 pipe D, whose function is to allow the entrance of air and "break" the siphon is introduced into the bend, this consisting of a wrought iron pipe with fittings comprising the T-coupling d, in one end of which is inserted a plug P, to permit cleaning upon occasion, if necessary.

35 Plate E consists of a casting with a bell F, as shown, and is set in the floor of the tank H and serves as a cover for the pot J. This bell F takes the discharge leg C, the same being leaded in so that both legs and plate E 40 form one part, being assembled at the foundry. The various drafts of this siphon are obtained by fitting differing lengths of legs between the iron bend B and plate E. On the under side of the plate, the discharging leg is produced at G, as shown in the drawing, to 45 reach below the water seal in the pot. Plate E is provided with a flange and a number of bolt holes. It is fastened to the pot by threaded bolts e, e, and nuts e', e'. This offers the very great advantage of permitting the legs and cover to be removed and a different draft 50 combination used instead. The pot J is an iron casting with a flange provided to receive plate E. This pot has one opening O for the discharge pipe, and is so arranged that it keeps a water seal over the lower end of the extension G of plate E.

M is an overflow pipe located in the flush tank H, 55 and connecting at its lower end with the sewer pipe L. The upper end of this overflow pipe extends to a level above that of the bend B of the siphon.

I represents a drainage hole in the plate E.

The operation of my invention is as follows: Water 60 flowing into the flush tank through the inlet I raises the level of the fluid mass therein until it flows through the bend B down into the pot J. Accumulating in this pot, it closes up the lower end of the extension G of the discharge leg of the siphon and produces a growing back pressure of air which raises the level of the fluid in the bend B of the siphon by a considerable amount. When the siphon is filled up nearly solid with fluid, the siphon action begins in the well known way and a rapid flow of material is discharged into the 65 pot J and through the sewer L, flushing the same out. When the level of material in the flush tank reaches the lower end of the vent pipe D, air is admitted to the bend B of the siphon, which breaks the siphon and stops the flow. If there were no drainage hole I, it 70 will be seen that the flush tank might be nearly filled and then if the inflow ceased, as frequently happens in the case of sewer systems of country houses which are left empty during the winter, the material would remain in the flush tank and on freezing would be 75 liable to break the siphon. The drainage hole I prevents any such long continuing accumulation, and the disadvantages resulting therefrom. In case the siphon is stopped up for any reason, the excess material will 80 escape through the overflow pipe M. In case the vent 85 pipe D becomes stopped up, the plug P may be removed, whereupon an opening will be formed in line with the bore of the main portion of the vent pipe so that it can be readily cleaned by inserting a rod. In 90 case of occasion to repair the siphon or change its draft, the cover E of the siphon may be easily removed by loosening the bolts and nuts e, e', when the joints can 95 be heated, the lead melted and the various sections of the siphon separated and new sections of the same or different length substituted, or a new cover with complete siphon giving desired draft substituted.

The advantages of my invention comprise the ease in setting up and taking down of the siphon; convenience in changing the draft by substituting legs of different lengths, all without removing the pot J from the concrete; ease of cleaning the vent pipe D and the drainage action by which the long continued standing of matter in the flush tank, when the sewer system is out of use, is avoided.

Having, therefore, described my invention, I claim:

1. In a sewer flushing apparatus, the combination of a flush tank, a pot set in the bottom thereof and extending below the same, a removable cover for said pot provided

with a discharging leg extending downward and a bell extending upward all made integrally with said cover, and a siphon having its discharge leg set in said bell.

2. In a sewer flushing apparatus, the combination of a flush tank, a pot set in the bottom thereof and extending below the same, a removable cover for said pot provided with a discharging leg extending downward and a bell extending upward all made integrally with said cover, and a siphon having its discharge leg set in said bell, the intake leg of said siphon being of larger diameter than the discharge leg.
3. In a sewer flushing apparatus, the combination of a flush tank, a pot set in the bottom thereof and extending below the same, a removable cover for said pot provided with a discharging leg extending downward and a bell ex-

tending upward all made integrally with said cover, screw threaded bolts and nuts for fastening said cover to said pot, and a siphon having its discharge leg set in said bell.

4. In a sewer flushing apparatus, the combination of a flush tank, a pot extending below said tank, a cover for the pot forming a portion of the bottom of the tank, a siphon in the flush tank having a discharge connection passing through the pot cover into the pot, and a leakage opening through said cover outside of the siphon. 20

Signed at New York, N. Y. this 27th day of March 1907. 25
